his Atty.

UNITED STATES PATENT OFFICE.

GEORGE W. MURRAY, OF SUMTER, SOUTH CAROLINA.

GRAIN-DRILL.

SPECIFICATION forming part of Letters Patent No. 644,032, dated February 20, 1900.

Application filed February 14, 1898. Serial No. 670,309. (No model.)

To all whom it may concern:

Be it known that I, GEORGE W. MURRAY, a citizen of the United States, residing at Sumter, Sumter county, State of South Carolina, have invented a new and useful Improvement 5 in Grain-Drills, of which the following is a specification.

This invention relates to a machine which has for its object to drop seeds in small fur- 10 rows at predetermined distances, which distances may be regulated at the will of the operator. This, together with other features of novelty, will be more particularly pointed out in the descriptions and claims and by reference to the drawings, in which—

Figure 1 is a longitudinal vertical section. Fig. 2 is a plan, part being broken away to show the interior construction. Fig. 3 is a detail view of the changing-gear and releas- 20 ing device for operating the seed-dropper. Fig. 4 is an enlarged section through the seed-dropper.

The machine is mounted upon a horizontal rectangular frame 1, which is supported upon 25 an axle 2, which has wheels 3 at either end, the axle 2 being secured to the wheels and turning with them in the journals 4, secured to the under side of the frame 1. The front end of the frame 1 is supported upon a caster-wheel 5, which is mounted in a fork 6, the fork being held in a journal 7 and provided with a tongue 8 for drawing and guiding the machine.

Across the front part of the machine ex- 35 tends a horizontal rod 9, which is secured to the frame 1 by brackets and braces in a secure and suitable manner. This rod 9 serves as a bearing for one end of the drag-bars 10, which terminate at their rear extremity in 40 the drill tubes or points 11, the drag-bars 10 being divided into pairs that are separated by collars on the rod 9 and joined together where they are secured to the drill-points 11, in this way holding the points 11 from any lateral 45 movement. The drag-bars 10, however, are journaled on the rod 9 and permit the drill-points 11 to be raised or lowered by swinging on the rod 9.

Mounted above the frame 1 is a hand-lever 50 12 of the usual type employed on this class of machinery, provided with the ordinary ratchet for securing the same in any desired position.

This hand-lever 12 has extending forward a connecting-rod 93, which connects with a crank 14, mounted upon a rotating shaft 15, 55 which revolves in journals 16, secured to either side of the frame 1, the shaft 15 being in length equal to the distance between the extreme drill-points. From the rod 15 extend a series of crank-levers 17 in a horizontal di- 60 rection when the hand-lever 12 is in its normal position. This series of cranks 17 are connected to the drag-bars 10 by rods 18, which are pivoted to the cranks 17 and provided with a permanent washer 19. Near the 65 upper end, surrounding the rod 18, between the washer 19 and drag-bars 10, is a coil-spring 20, the lower end of the spring resting on a perforated block 21, which is secured between each pair of the drag-bars 10. The 70 rod 18 passes through the perforation in the block 21 and terminates in a nut-head on the under side of said block 21. A hook 22 is secured to each of the drag-bars 10, and when the said arms are raised to their extreme limit 75 11 from contact with the ground.

Above the frame 1 is a seedbox 23, mounted on suitable rods or brackets. The bottom of 80 the seedbox 23 inclines toward the center and has a longitudinal slot extending from one end to the other thereof. Through this slot passes a revolving rod 24, which completely fills the longitudinal slot. This rod 85 is provided with a series of small orifices cut out from the rod, the said orifices usually being arranged in a spiral form around the rod 24. Underneath the seedbox 23 is a series of funnels 25, which occupy the entire length 90 of the seedbox, the funnels being the same in number as the drill-points 11. These funnels 25 terminate in dropping-tubes 26, which empty into the upper end of the drill-points 11. On the axle 2, at one extremity and beyond the driving-wheel 3, there is mounted a sprocket-wheel 27, which connects by a chain with a second sprocket-wheel 28, the said wheel 28 being mounted upon a shaft 29, which has its journals secured to the seed- 95 box 23. From the shaft 29 there extends a pendent bar 30, and from the end of the shaft 29 there extends a bar 31, which is curved outwardly, and these bars 30 and 31 hold 100

a short shaft 32 at their outer ends. A sprocket-wheel 33 on the shaft 29 connects with a sprocket-wheel 34 on the shaft 32 by chain 35. This shaft 32 also carries a gear-wheel 36, and the end of the rod 24 terminates on the outside of the seedbox 23 in a cone series of gears 37, with which the gear-wheel 36 meshes. The gear-wheel 36 can be moved longitudinally upon the shaft 32 and secured at any desired point, so as to engage any of the series of gears in the cone 37, it being evident that when the gear 36 engages the largest of the gears in the cone 37 the rod 34 will revolve slowly and comparatively few seed will be dropped through the tube 26 and drill-points 11. On the other hand, when the gear 36 engages the smallest of the gears in the cone 37 the rod 24 will revolve much more rapidly and the seed will be dropped more frequently from the seedbox 23. There being a series of the gears in the cone 37, it is evident that a range of speed for dropping the seed may be obtained.

Mounted upon suitable brackets secured to the seedbox 23 is a shaft 38, which carries a small hand-lever 39, provided with the usual ratchet for holding the same in any desired position. This shaft 38 has extending from the outer end of the same a small crank 40, the outer end of which engages a connecting-rod 41, which serves to connect the crank 40 with the shaft 32.

The operation of this machine is as follows: The hand-lever 12 is pushed forward to the extreme limit. This through the connecting-rod 13 and crank 14 revolves the shaft 15, moving the series of cranks 17 in an upward direction and drawing the drill-points 11 up and clear from the ground. The small hand-lever 39 is drawn back toward the seedbox as far as the same will move. This movement raises the crank 40 and by the connecting-rod 41 lifts the shaft 32, taking the gear-wheel 36 out of engagement with any of the gears in the cone 37. The machine is then driven to the desired point in the field, when the small hand-lever 39 is pushed forward until the gear-wheel 36 engages the gear in the cone 37 with which it is in line. The particular gear in the cone 37 with which the gear 36 engages having been previously determined by the operator and the gear 36 having been set at the required position on the shaft 32, the hand-lever 12 is now drawn back, which movement depresses the drill-points 11 until they cut deep enough into the ground. The farther the hand-lever 12 is brought back the farther the points 11 enter into the earth. The machine is now driven forward, and the rotation of the wheels 3 and axle 2 causes the rod 24 to revolve through the mechanism of the sprocket-wheels and gears before mentioned. The rod 24 successively presents the small orifices to the interior of the seedbox 23. The seed fills the small orifice, which as it revolves passes the bottom of the box 23 and opens into the series of funnels 25, from

which the seed drops through the dropping-tube 26 and into the hollow drill-points 11, the lower end of the drill-points 11 depositing the seed in the earth just back of the lowest excavation made by the drill-point 11.

If one of the drill-points 11 strikes any obstruction, such as stone or root, the obstruction will push the drill-point up, the small block 21 sliding up on the rod 18 and compressing the coil-spring 20. As soon as the obstruction is passed the coil-spring 20 forces the drill-point back to the level of the balance of the drill-points. If it is desired to use only a limited number of the drill-points 11, such points as are not to be used are raised and the hooks 22 passed over the rod 15. The dropping-tubes 26 are disengaged from the funnels 25 and supporters are placed within the mouth of the funnel.

Having described my invention, I claim—

1. The herein-described drill comprising a supporting-frame, drag-bars pivotally mounted therein, drill tubes or points carried by said drag-bars, a transverse rock-shaft mounted on said frame, a crank-arm secured thereto, a hand-lever pivoted to said frame and connected by a pitman with said crank-arm, a series of arms extending from said rock-shaft, rods connecting said arms and said drag-bars, springs encircling said rods, and hooks carried by said drag-bars and designed to engage said rock-shaft, substantially as set forth.

2. The herein-described drill comprising a supporting-frame, drag-bars pivotally mounted therein, drill-tubes carried by said drag-bars, a transverse rock-shaft mounted on said frame and having a series of arms extending therefrom, means for rocking said shaft, a series of perforated blocks carried by said drag-bars, headed rods extended through the perforations of said blocks and connecting the same with the arms of said rock-shaft, washers secured to said rods, and springs interposed between said blocks and said washers, substantially as set forth.

3. The herein-described drill comprising a supporting-frame, a transverse rod mounted therein, drag-bars having their forward ends spaced apart and pivoted to said rod, drill-tubes carried by said drag-bars, a seedbox carried by said frame and having a longitudinal slot in its bottom, a rotatable shaft mounted in said slot and having a series of spirally-arranged recesses, means for varying the speed of rotation of said shaft, hoppers located below said seedbox, and tubes connecting said hoppers with said drill-tubes, substantially as set forth.

4. The herein-described drill comprising a supporting-frame, a transverse rod mounted therein, drag-bars having their forward ends spaced apart and pivoted to said rod, drill tubes or points carried by said drag-bars, a seedbox carried by said frame and having a longitudinal slot in its bottom, a rotatable shaft mounted in said slot and having a series of spirally-arranged recesses, means for

varying the speed of rotation of said shaft, and connections between said seedbox and said drill tubes or points, substantially as set forth.

5. The herein-described drill comprising a main frame, drill-tubes carried thereby, a seedbox having a longitudinal slot in its bottom, a shaft mounted in said slot and having a series of spirally-arranged recesses, a cone series of gears keyed to said shaft, a shaft mounted adjacent said seedbox, means for rotating said shaft, a sprocket-wheel mounted on said shaft, a second shaft mounted adjacent thereto and also carrying a sprocket-wheel, a chain connecting said sprocket-wheels, a gear-wheel also mounted on said second shaft and designed to mesh with said cone-gears, means for adjusting said gear-

wheel, and connections between said seedbox and said drill-tubes, substantially as set forth.

6. The herein-described drill, comprising a supporting-frame, drag-bars pivotally mounted therein, drill-tubes carried by said drag-bars, a transverse rock-shaft mounted on said frame, hooks carried by said drag-bars and designed to engage said rock-shaft, connections between said rock-shaft and said drag-bars, means for rocking said shaft, and means for feeding seed to said drill tubes or points, substantially as set forth.
